UNITED STATES PATENT OFFICE.

CHRISTIAN AALBORG, OF PITTSBURGH, PENNSYLVANIA, ASSIGNOR TO WESTINGHOUSE ELECTRIC & MANUFACTURING COMPANY, A CORPORATION OF PENNSYLVANIA.

RHEOSTAT MECHANISM.

Application filed March 23, 1920. Serial No. 368,137.

My invention relates to rheostat mechanisms and particularly to motor-operated rheostat mechanisms.

One object of my invention is to provide a rheostat mechanism of the above-indicated character that shall be simple, compact and relatively inexpensive in construction, and that shall have the propelling motor supported along the axis of rotation of the rheostat contact arm.

In many electrical systems now in service, a motor-operated rheostat is used to vary the resistance value of various circuits. Thus, in many types of regulator systems, motor-operated rheostats are provided for varying the excitation of the generators connected to the main supply circuit and regulators are provided for governing the operation of the motors in accordance with the electrical conditions obtaining on the supply circuit.

In a rheostat mechanism constructed in accordance with my invention, the various contact terminals are arranged in concentric circles and a rotatable contact arm is provided with brush members which engage the contact members. The brush members are so supported on the contact arm as to be movable perpendicularly into engagement with the contact members. Spring members are provided for biasing the brush members into engagement with the contact members. A stop member is provided in the path of the contact arm for limiting the movement of such arm. A motor is supported along the axis of rotation of the contact arm and is mechanically connected to such arm by a worm-gear mechanism and an overrunning clutch. The overrunning clutch permits the free rotation of the motor when the contact arm engages the above mentioned stop member. The leads which are connected to the motor are preferably carried through a base plate of the device and through the supporting member for the motor at the center of rotation of the contact arm.

In the accompanying drawing, Figure 1 is a front elevational view of a rheostat mechanism constructed in accordance with my invention; Fig. 2 is a sectional elevational view of the mechanism shown in Fig. 1; Fig. 3 is a sectional view of the worm gearing between the motor and the contact arm; Fig. 4 is a detail view of one of the

brush members; Fig. 5 is a plan view of the supporting frame for the brush members; Fig. 6 is a side elevational view of the supporting frame; Figs. 7 and 8 are detail views of a spacing member for the brush members; Figs. 9, 10 and 11 are detail views of one of the brush members, and Fig. 12 is a detail view of a terminal cap.

Referring particularly to Figs. 1, 2 and 3 of the drawing, a supporting base 1, composed of any suitable insulating material, is provided for supporting contact members 2 which are disposed in concentric circles 3, 4 and 5. A contact ring 6 is mounted upon the base 1 adjacent to the inner row 5 of contact members and within the ring 6 is mounted a row of contact members 7 and a contact ring 8. A contact arm 9 is provided for engaging the contact members and the contact rings, and a motor 10 is provided for operating the contact arm 9.

The contact arm 9 comprises a supporting member 11, which has a bearing upon a hollow shaft 12, and a brush mechanism 13 which is connected to the supporting member 11. The arm 9 may be manually actuated by a handle 9^a forming a part thereof. The conductor leads for the motor extend through the shaft 12 which is fitted to a supporting plate 14 and is held in position by a nut 15. The supporting plate 14 is mounted upon one side of the base member 1 and is connected to a second supporting plate 16 on the opposite side of the base member by means of any suitable bolts or rivets 17. The plate 14 is provided with a projecting portion 18 which is engaged by a lug 19 on the arm 9 to limit the movement of such arm.

The brush mechanism 13, which is shown more in detail in Figs. 5 to 12, inclusive, comprises a supporting block 20, of any suitable insulating material, preferably bakelite micarta, which is connected, in any suitable manner, to the supporting arm 11. The brush member 21, which engages the contact ring 8 and the contact members 7, is connected to the insulating block 20 in any suitable manner, as by screws 22. A brush frame 23 is connected to the outer end of the insulating block 20 and serves to support the brush members 24, 25, 26 and 27, which respectively engage the contact members of rows 3, 4, and 5 and the contact ring 6. The frame 23 comprises two members 28

and 29 which are riveted together to provide a U-shaped supporting portion having arms 30 and 31 and a yoke portion 32 which fits over, and is attached to, the outer end of the block 20.

A clamp member 33 is attached to the outer end of the supporting frame 23 and serves to hold the brush members 24 to 27, inclusive, in position. A spacing member 35, of any suitable insulating material, is disposed in the frame 23 between the brush members 26 and 27. Each of the brush members 24 to 27, inclusive, is composed of any suitable metallic material and the brush member 24, which is illustrated in Figs. 9, 10 and 11, will be described in detail. The brushes 25, 26 and 27 are similar in construction to the brush member 24. The brush member 24 is provided with a slot 36 within which the arms 30 and 31 of the frame 23 are disposed and a hole 37 is drilled through a portion of the brush member to provide space for mounting a spring member 38.

The spring member 38 is located between the arms 30 and 31 of the frame member 23. One end of the spring member 38 engages the arm 30 and the other end engages a washer 39 which impinges upon the brush member 24 to force it in engagement with the row of contact members 3. A contact cap 40 is riveted or is connected by screws to the top portion of the brush member 23 and is connected to a conductor 41 in any suitable manner. Thus, the brush member 24 is supported upon the arms 30 and 31 of the frame 23 and is forced perpendicularly into engagement with the row of contact members 3 by means of the spring member 38. The brush members 25 to 27, inclusive, are constructed in a similar manner in order that they may be moved perpendicularly into engagement with the rows of contact members 4 and 5 and the contact ring 6.

The frame 43 of the motor 10 is provided with an extended portion 44, which is rigidly mounted upon the end portion of the shaft 12. The armature shaft 45 of the motor 10 is connected to the contact arm 9 by means of a worm-gear mechanism 46 and an overrunning clutch 47.

The worm-gear mechanism 46 comprises a worm 48, which is keyed in any suitable manner to the armature shaft 45, a worm pinion 49, which meshes with the worm 48, and a worm 50 which meshes with a worm wheel 51 and which is directly connected to the worm pinion 49. The worm pinion 49 and the worm 50 are mounted, in any suitable manner, upon the extended portion 44 of the motor frame, and the worm wheel 51 is rotatably mounted upon an extended portion 52 of the supporting member 11 which surrounds, and is mounted upon, the shaft 12.

The overrunning clutch 47 serves to con-

nnect the worm wheel 51 with the member 11 of the contact arm 9. The worm wheel 51 is provided with an extended portion having pockets 54 and 55 in it. The pockets 54 and 55 serve to support two spring members 56 and two balls 57. The two spring members 56 serve to force the balls 57 into grooves 58 which are formed in the supporting arm 11. Although only two pockets 54 and 55 are provided in the extended portion of the worm wheel 51, it is apparent that any number of such pockets may be provided for supporting any number of spring-and-ball members which engage the sides of the grooves cut in the supporting arm 11. It is preferable to have the grooves 58 extend completely around the concave portion of the supporting arm 11 which is engaged by the ball members 57. The overrunning clutch 47 serves to permit the rotation of the motor 10 whenever the lug 19 on the contact arm engages the projecting portion 18 on the plate 14.

In a rheostat mechanism constructed as above set forth, all the parts are supported upon the base member 1 and, in case it is necessary to make any repairs, it is only necessary to disconnect the motor leads, loosen the nut 15 and lift the contact arm 9 and the motor 10 from the base plate 1. If desired, the motor leads may be carried directly to the motor 10 without passing through the base plate 1 and, in such case, it would only be necessary to disconnect the nut 15 from the shaft 12 to remove the motor and the contact arm from the base plate.

Modifications in the device and in the arrangement and location of parts may be made within the spirit and scope of my invention, and such modifications are intended to be covered by the appended claims.

I claim as my invention:—

1. In a rheostat mechanism, the combination with a plurality of contact members and a contact arm for sliding over and engaging said contact members, of a motor for operating said contact arm, and means comprising a handle for manually actuating said arm independently of said motor while maintaining the mechanical connections thereof.

2. In a rheostat mechanism, the combination with a plurality of contact members, and a rotatable contact arm for sliding over and engaging said contact members, of a motor for operating said arm and means for supporting said motor along the axis of rotation of said arm manually operable means for independently actuating said arm while maintaining the mechanical connections of said motor.

3. In a rheostat, in combination, a plurality of contact members, a contact arm disposed to engage the contact members, a motor adapted to rotate the contact arm,

means adapted to limit the angular movement of the contact arm and a clutch interposed between the motor and contact arm, said clutch including a rigid clutch member 5 provided with a friction face and a second clutch member resiliently retained continuously in engagement with said rigid clutch member, thereby to permit independent rotation of the motor when the contact arm 10 is held against angular movement.

4. In a rheostat mechanism, the combination with a plurality of contact members, a rotatable contact arm for engaging said

contact members, and a stop member for limiting the movement of the contact arm, 15 of a motor supported along the axis of rotation of said contact arm, and means comprising a plurality of yieldingly mounted balls for yieldingly connecting the motor to the contact arm to permit the 20 rotation of the motor when the arm engages said stop member.

In testimony whereof, I have hereunto subscribed my name this 13th day of March, 1920.

CHRISTIAN AALBORG.
